BLAST FURNACE COOLING PLATE

Herman F. Dobscha, North Braddock, Pa.

Application August 1, 1940, Serial No. 349,260

3 Claims. (Cl. 122—6.1)

This invention relates to cooling elements for blast furnace walls, and more particularly to a novel design of cooling plate having two separate and independent compartments in which the cooling medium is circulated.

Double compartment cooling plates of various designs have long been used for controlling the temperature of blast furnace walls. Usually the double compartment is provided by a front portion and a rear portion. The purpose of such construction is that in the event that the forward end of the plate, which is subjected to the greatest heating effect and to abrasive action by the stock, becomes damaged, some degree of cooling effect may be retained by operation of the rear portion. To obtain better heat exchange, the cooling plates are usually provided with a system of baffles positioned within the front and the rear portions or at least in the latter.

It has been my experience that all of the various prior designs have objectionable features which cause their use to be less than completely satisfactory. For example, the water which is usually employed as a cooling medium can economically be given only a limited amount of conditioning before using it in the cooling system. The hard constituents of the water, together with silt and other particles which may be entrained therein, become deposited upon the interior surfaces of the plates and by cumulative action, a heavy layer of such material is rapidly built up. In the prior designs, this deposition is greatest upon the front portion of the double compartment cooling plates at which points the temperature of the plate surface is much higher. The scale formation accumulates similar to that observed in water tube boiler installations which become encrusted with scale. As the quantity of water required for each cooling plate is usually on the order of 20 to 40 gallons per minute, there is a practical limit to the amount of straining which can be done. Consequently, when the necessary water is obtained from a source such as a river, a large quantity of silt and sand is carried by the cooling water and deposited in the cooling plate interior.

In the double compartment cooling plates used heretofore, the front compartment is of considerably larger volume than that of the plate which I have designed. Accordingly, for a given volume of water, the velocity of the cooling water, and consequently its scouring action, is much less than in my design.

The front compartments of older designs also

include a contiguous channel which extends rearwardly at the side of the plate. Thus, both the front portion of the plate and a substantial part of the rear portion are cooled by the one water circulation. In the event that the front portion becomes damaged and the water supply to this portion is shut off, the major part of the cooling effect is lost.

It is the object of my invention to eliminate the disadvantages and limitations of prior designs and to provide double compartment cooling plates of improved construction which have an inherent self-clearing action and in which the major portion of the cooling effect is retained after failure of the front compartment.

Another object of my invention is to provide a cooling plate constructed and arranged in the specific manner herein set forth, so that the casting practice is simplified.

These and other objects of my invention will be apparent in the following description, considered in conjunction with the accompanying drawing, in which:

Figure 1 is a fragmentary sectional view of a blast furnace wall showing the cooling plates installed therein.

Figure 2 is a horizontal section of my improved cooling plate.

Figure 3 is a longitudinal section on line III—III of Figure 2.

Figure 4 is a section on line IV—IV of Figure 2.

Referring to the drawing, there is shown in Figure 1 a furnace wall 2 in which is installed a plurality of cooling plates. Each of the improved plates 3 comprises a one-piece casting usually formed of copper or bronze, having top, bottom, front, rear, side and intermediate walls. Near the front end of the plate 3, the intermediate wall 5 forms the forward or nose compartment N. Extending rearwardly from the partition 5 is an integral vertical rib 6 which, in conjunction with a pair of similar ribs 7 extending forwardly from the rear wall 8 of the plate, forms a system of longitudinally extending baffles for the rear compartment R.

The rear wall 8 is provided with two pairs of holes 9 and 10, in spaced relation between the baffles 7 and the side-walls 11 of the plate. The outer pair of holes, 9—9, is threaded to receive respectively a water supply pipe 12 and a water exit pipe 13. The inner pair of holes, 10—10, are smooth or unthreaded, as shown, and are of the proper size to permit the insertion therethrough of a water supply pipe 14 and a water exit pipe 15. A pair of holes 16—16 is provided in the partition

5 and these holes are threaded to receive the forward ends of the pipes 14 and 15.

The forward or nose compartment N of my improved plate is of comparatively shallow depth and volume in comparison to the similar space in prior designs of plates. While it is unnecessary to maintain any particular ratio between the cross-section of the water supply pipes and the transverse section of the nose compartment, I prefer to use supply and return pipes which have a cross-sectional area of about 10 per cent to 20 per cent of that of the transverse nose section N. By so doing, I have found that using 20 to 40 gallons of water per minute at a pressure of about 20 pounds, I will obtain a sufficient degree of scouring action in the nose compartment to keep the solid particles—sand and silt—in motion and prevent their becoming lodged or deposited in this compartment.

It is noted that by projecting the nose compartment water supply and return pipes 14 and 15 respectively, completely through the rear compartment and into the shallow depth nose compartment N, the water is caused to flow at high velocity through supply pipe 14 and impinge directly upon the front wall of the nose compartment N with undiminished force and to move with a turbulent scouring action to the exit pipe 15.

Heretofore, the provision of baffles has complicated the casting of double compartment cooling plates, and it is necessary, in the prior designs, to cast the plates flat, that is to say, with the greater dimensions in a horizontal plane. The result of such prior practice is that frequently the nose portion of the plate is cast in non-uniform thickness. Since it is this portion of the plate which is subjected to abrasive action and directly exposed to the highest temperature, failure of the prior art plate is often attributable to this condition of non-uniform thickness of the nose portion.

In the plate of my invention, the longitudinal disposition of the baffles 6 and 7 and the overall design of the plate is such that the plate may be cast upright, that is, with its baffles vertically disposed and the nose portion at the bottom of the mold. A solid dense nose portion is thereby obtained, and the use of anchors, required in prior art constructions, is eliminated.

I claim:

1. A cooling element comprising a body having top, bottom, front, rear and intermediate and side walls defining a comparatively small forward compartment and an independent comparatively

large rear compartment, a pipe passing through the rear wall and screwed into the intermediate wall for impinging a cooling medium directly against the front wall of said forward compartment and means for circulating a cooling medium in said rear compartment, a plurality of baffles integral with the top and bottom walls of said body and extending longitudinally in the latter compartment, and being of less length than the longitudinal dimension between said rear wall and said intermediate wall.

5 2. A cooling element comprising a cast metal body having a comparatively small forward compartment and a separate compartment of materially larger volume to the rear thereof, respective inlet and outlet pipes communicating with the forward compartment for impinging a cooling medium directly against the front wall thereof and for discharging the cooling medium, said 15 pipes passing through the rear wall of said rear compartment and firmly secured in the rear wall of said forward compartment, and respective baffles extending forwardly from the rear wall of said rear compartment and rearwardly from the rear wall of said forward compartment.

20 3. A cooling element of the character described, comprising a shallow metallic body having top and bottom walls, side walls integral therewith, a forward end wall and an intermediate wall integral with said upper and lower and side walls, said forward end wall and said intermediate wall defining with said top, bottom and side walls a forward compartment of comparatively small volume, a rear wall spaced a considerable distance 25 from the intermediate wall and defining with the top, bottom and side walls a rear compartment of considerably larger volume than the forward compartment, respective inlet and outlet pipes communicating with the said rear compartment, 30 other inlet and outlet pipes having smooth unthreaded portions where they extend through said rear compartment, the ends thereof being threaded into said intermediate wall, said pipes being effective to provide for the rapid circulation 35 of a cooling medium through said forward compartment, and respective baffles located between said pipes and projecting forwardly from said rear wall and rearwardly from said intermediate wall, the respective longitudinal dimensions of 40 said baffles being less than the distance between the inner faces of said rear wall and said intermediate wall.

50 HERMAN F. DOBSCHA.
